UNITED STATES PATENT OFFICE.

ARTHUR N. BACHRACH, OF NEW YORK, N. Y., ASSIGNOR TO SAMUEL L. BACHRACH, OF NEW YORK, N. Y.

DESIGN FOR A NECKTIE.

47,708.

Specification for Design.

Patented Aug. 17, 1915.

Application filed March 27, 1915. Serial No. 17,546. Term of patent 7 years.

To all whom it may concern:

Be it known that I, ARTHUR N. BACHRACH, a citizen of the United States, residing in the city of New York, county of New York, and State of New York, have invented a new, original, and ornamental Design for Neckties, of which the following is a specification, reference being had to the accompanying drawing, forming part thereof.

Figure 1 is a perspective view of a necktie, showing my new design; Fig. 2 is a face view of the same; and Fig. 3 is a front elevation showing the aspect of a necktie embodying my improvements when tied in the conventional manner.

I claim:

The ornamental design for a necktie, as shown.

ARTHUR N. BACHRACH.
